UNITED STATES PATENT OFFICE.

JOSEPH CASALE, OF NEW YORK, N. Y.

FOLDING UMBRELLA.

No. 884,712.

Specification of Letters Patent. Patented April 14, 1908.

Application filed May 20, 1907. Serial No. 374,555.

To all whom it may concern:

Be it known that I, JOSEPH CASALE, of the city, county, and State of New York, have invented a new and useful Improvement in 5 Folding Umbrellas, of which the following is a full, clear, and exact description.

My invention relates to improvements in folding umbrellas, and the object of my invention is to produce a practical and convenient umbrella, in which the stick is made of telescoping parts, and in which the ribs and braces also telescope.

My invention is intended to produce an umbrella in which the frame and stick will 15 all easily and quickly reduce to a small compass so that it can be conveniently carried or packed, and also to construct the parts so that the umbrella can be easily opened, and will serve the purposes of the ordinary umbrella.

With these ends in view, my invention consists of certain features of construction and combinations of parts which will be hereinafter described and claimed.

Reference is to be had to the accompanying drawings forming a part of this specification, in which similar figures and letters of reference indicate corresponding parts in all the views.

Figure 1 is a side elevation of the framework of the umbrella with the parts in open position. Fig. 2 is an enlarged detail section on the line 2.2 of Fig. 1. Fig. 3 is a broken sectional plan on the line 3.3 of Fig. 2. Fig. 4 is a vertical section through one of the joints of the telescoping stick parts. Fig. 5 is a detail in section of one of the rib joints. Fig. 6 is a plan of the same. Fig. 7 is a detail of one of the brace joints. Figs. 8 and 9 are details in front and side elevation of the means for pivoting the ribs and their catches.

Fig. 10 is a longitudinal section of the umbrella in folded position. Fig. 11 is a cross section on the line 11.11 of Fig. 10. Fig. 12 is a detail section on the line 12 of Fig. 10. Fig. 13 is a cross section on the line 13.13 of Fig. 10. Fig. 14 is a cross section on the line 14.14 of Fig. 10, and Fig. 15 is a longitudinal section of a modified form of umbrella stick.

In the drawing I have shown the umbrella without a cover, which is applied as usual, so that the parts may not be confused.

The umbrella is provided with the usual stick, except that the parts 10, 10^a, 10^b and 10^c are hollow and telescope one within the other. The lower and larger telescopic part

10 is provided with a handle 11 of some sort, and the upper part 10^c is screwed into the nut 12, which forms a part of the crown of the umbrella. This nut 12 abuts with a 60 surface nut 13, and a ring 14 is arranged between the two nuts, and screws upon the threaded and reduced outer part of the nut 12, as shown clearly in Fig. 10. The nut 12 also fits on the threaded thimble 15, and the nut 13 also screws to the thimble 15, and the threaded ring 14 which fits upon the reduced part of the nut 12, is clamped between the nuts 12 and 13, and serves to lock the inner ends of the umbrella ribs, as hereinafter described. The ring 14 is cut away on one side as shown at 14^a in Fig. 11, so that by turning it, the open part can be brought above the pivots of the umbrella ribs and enable them to be easily put in place, as will appear below. On the outer end of the thimble 15 is screwed a thin nut 16, between which and the nut 13 is clamped one end of the rubber or other hood 17, the other end being clamped between the head 18 of the center rod presently referred to and the nut 19 on the said rod 20, and so when the rod is pushed up as shown in Fig. 1, to the position which it assumes when the umbrella is opened, the hood 17 will prevent the water from running 70 into the thimble 15 and so leaking down around the umbrella stick. 75

The rod 20 extends down into the part 10^c of the umbrella stick, and serves as a stiffener to stiffen the said stick. It is flattened at its 80 upper and outer end portion and has a reduced cylindrical part 21, and when the rod is pulled out through the opening in the thimble 15, the part 21 will permit it to be turned half around, so that it will lock over 95 the walls of the thimble 15 and hold the rod extended.

At the upper end of each section of the stick is a rib 22 formed by pressing out the material of the stick section, and this forms 100 a recess to receive the catches 23 which are arranged in pairs near the lower ends of the stick sections, and are held on opposite members of the bow shaped spring 24, which is held upon a cross pin 25 in the lower ends 105 of the stick sections, so that when the sections are pulled out, the catches 23 will push through the holes in the particular section in which they are held, and enter the recesses formed on the inner walls of the ribs 22, and 110 so hold the stick in extended position. When the stick is pushed together, the

rounded upper ends of the top spring 24 enter the recess 23^a in the stick 20 (see Fig. 10), which pulls the ends of the top spring 24 together, thus releasing its catch 23, and the continued movement causes the lower end of the top section 10^a to engage the next spring 24 below, and so on until each spring is closed and its catches released.

The umbrella is provided with ribs 26 arranged in a general way as umbrella ribs usually are, and the sections are of the conventional inverted U shape in cross section, and slide one within the other. The inner section 26 of each rib has its sides pivoted between ears 27 on the nut 12, and the ribs normally tend to spring open by reason of the tension of the coil springs 28, which are curled around the pivots 29 of the ribs, and the free ends of the springs press respectively against the nut 12 and the backs of the ribs. It will now be seen that by turning the ring 14 to bring the part 14^a above one of these joints, enables the joint to be easily reached, and a rib inserted or removed. This makes it easy to assemble the parts or to repair the umbrella if necessary.

The rib sections 26 slide one within the other, and at the outer ends of all but the outer section, the several sections have inner edges 26^a, which serve to guide the next succeeding section, as shown in Fig. 5. At these points or joints, the outside rib section has lugs 30, which are perforated, so that the cover can be attached therein, and these lugs carry springs 31, which are yieldingly pivoted in the lugs, and each spring has a catch 32 at its free end, which projects through the slot in the outside section in which it is mounted, and through the hole 33 in the inside section, as shown clearly in Fig. 5. The catch 32 is inclined on the side next the outer end of the rib, so that when the next succeeding rib is pushed inward against it, it will free the catch and permit the telescoping. To provide for starting this unlocking action, the outer section of all has within it a rod 34, which is shown clearly in Fig. 10, and this has an inturned outer end as shown at 35, which when the umbrella is folded, rests upon the flange 59, to be hereinafter referred to, and which in the said position is held also beneath a ring 45, also to be referred to presently. When the umbrella is opened, the part 35 engages the part 46, (see Fig. 10,) and so the sections are pulled out one from the other, but when the reverse action takes place, the outer section 26 slides in toward the umbrella stick, through the next section, the rod 34 strikes the first catch 33, and releases it, the inner end of the next section 26 strikes the next inner catch 33 and releases it, and so on until all the catches are released.

The umbrella is provided with telescoping brace sections 36, which are arranged in substantially the usual way, and extend from

the ribs to the runner 37, which is made up of numerous parts to be presently referred to. The brace sections, where they meet are each made to overlap the adjacent section, as shown at 38, and this is clearly seen in Fig. 7. The inner section also has a hole in the back as shown at 39, which registers with a smaller hole 40 in the outer section, and an in-turned spring part 41 of the inner section serves to press the end 42 of the catch rod 43 through the holes 39 and 40, and this holds the brace in extended position. The catch rod 43 lies partly within the inner section 36, and is pivoted to the same carrier 44 which carries its brace, but at a point a little below the carrier, so that the catch rod 43 and brace section 36 swing on different centers, and when the parts are extended, they assume a position shown in Fig. 7, but when the umbrella is folded and the runner 37 pulled down, the catch end 43 pulls out of the hole 40 and allows the sections or members 36 to slide together. The carriers 44 are little sheet metal devices, which are dovetailed into the supporting ring or flange 45, and are held in place by the ring nut 46 which serves the double purpose of preventing the carriers from falling out and engaging the ends 35 of the rods 34, as already described. The flange 45 is formed on the sliding sleeve 47, and this has its outer ends turned in and formed into spring members 48, which slide on the umbrella stick and serve to steady the runner. The sleeve 47 has a limited movement on the second sleeve or tube 49, which slides up and down the umbrella stick and also forms a part of the runner, and the movement of the parts 47 and 49 with relation to each other, is limited by the pin 51, which is fast in the part 47, and slides in the slot 50 of the part 49. The sleeve 47 has a spring latch 52 which extends through the slot 53 in the sleeve, and through a corresponding slot in the tubular member 49, and engages one of the annular ribs 22 of the umbrella stick. In this connection it should be noticed that the middle rib 22^a of the umbrella stick is too wide to enter the notch 54 in the catch 53, and so this catch engages only the lower and upper ribs 22, thus holding the umbrella in closed or open position as desired. The tubular part 49 of the runner extends down and merges into a cylinder 55, which is preferably milled on the outside, so that it can be gripped readily, and this has a series of pistons 56 which are radially arranged and suitably guided, and are pressed by springs 57 into engagement with the umbrella stick so as to steady the runner at its lower end. Just above the cylinder 55 and on the sleeve 47, are up-turned flanges 58 and 59, concentrically arranged, and forming between them a recess to receive the ends of the folded umbrella ribs, while the part 59 also serves to support the in-turned ends 35

of the rods 34. The flanges 58 and 59 are also attached to and concentric with the sleeve 60, which is normally pressed up by a spring 61, coiled around the sleeve 47, and held against a nut 62. This arrangement enables the flanges 58 and 59 which serve as catches, to be moved so as to release the rib ends, if desired.

In Fig. 15 I have shown a slight modification of the umbrella stick construction, in which the parts are normally opened by the tension of internal springs 66, and the parts are closed by means of a pull cord 64, which is attached to a cross-pin 63 in the upper section 10^b, and has a pull ring 65 below the handle.

When the umbrella is to be opened, the operator grasps the crown and the part 57 of the runner, and pulls out the whole affair longitudinally, and this causes the stick to be elongated and pulls the rib sections and brace sections into extended position, after which the umbrella runner 37 is pushed up, and the catch 54 engages the rib 22 and holds the umbrella open. To close it the catch 54 is released, the runner pulled down as usual, and the parts telescope as already described.

Having thus fully described my invention, I claim as new and desire to secure by Letters Patent:

1. A folding umbrella having a stick formed of telescoping parts, the sections of the parts having annular ribs thereon which have recesses on their inner sides, and some of which serve on their outer sides as catches for the umbrella runner, in combination with spring catches on the inner sides of the stick sections, adapted to enter the aforesaid recesses, and a runner having a latch to engage some of the aforesaid ribs.

2. A folding umbrella having a telescopic stick, a stiffening rod held in the upper section of the stick and extending through the umbrella crown, a crown, means for fastening the top of the stiffening rod in extended position, and a flexible hood having one part secured to the rod and another to the crown whereby the crown and rod are loosely connected.

3. In an umbrella having telescopic stick

sections, the combination with the said sections having adjacent parts recessed, of U shaped springs held within the sections and provided with catches to engage the recesses of the sections and hold them in open position, said catches having prolonged free ends and means for engaging said ends and releasing the catches. 55

4. In an umbrella of the kind described, the combination with the telescoping stick sections, of the bow shaped spring catches pivoted through their centers and adapted to project through holes in the inner sections and enter recesses in the outer sections, said catches having prolonged free ends, and sliding means for pressing the free ends of the catches together to release them. 60

5. The combination with the umbrella stick, the runner thereon and the telescoping rib sections, of the telescopic braces connecting the runner with the sections, and catch rods pivoted to the runner below the pivots of the inner brace sections, said catch rods lying within the inner brace sections and having their outer ends shaped to project 75 through holes in adjacent inner and outer brace sections.

6. The combination with the telescoping stick, ribs and braces, of the runner sliding on the stick and having a catch to engage projections thereon, springs secured to the runner and projecting upwardly and inwardly thereof so as to impinge on the stick, and a series of spring pressed plungers arranged around the stick below the runner so as to 85 impinge on the stick.

7. The combination with the telescoping stick, ribs and braces, of the runner on the stick, the catches to hold the ribs extended, said catches being arranged to open by end- 90 wise pressure towards the stick, and the slide rods in the outer sections of the ribs, the said rods having inturned ends and means on the runner to engage the said in-turned ends when the umbrella is folded.

JOSEPH CASALE.
